CLAIM

(57) The ornamental design for a mounted computer, as shown and described.

DESCRIPTION

FIG. 1 is a perspective view of a mounted computer according to our new design, where the broken lines shown in the drawings illustrate portions of the computer that form no part of the claimed design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a back perspective view thereof.
